BOTTLE STOPPER SEALING STRIP
REMOVER

Arthur B. Dodge, Lancaster, Pa.

Application February 2, 1939, Serial No. 254,327

4 Claims. (Cl. 215—46)

This invention relates to improvements in bottle stopper sealing strip removers.

The principal object of the present invention is to provide an improved means for facilitating the breaking or removal of bottle stopper sealing strips from bottles and the like.

A further object is the provision of a sealing strip remover having means for cleanly and neatly severing the strip adjacent the top rim or edge of the bottle mouth.

These and other objects and advantages will be apparent as the description is considered in connection with the accompanying drawing, wherein:

15 Figure 1 is a side elevation partly in section and partly broken away, of a bottle showing the invention applied thereto;

Figure 2 is a cross section of my stopper showing the split ring mounted thereon; and

20 Figure 3 is a perspective view of the split ring.

Referring more particularly to the drawing, wherein like reference characters designate similar parts throughout the several views, the numeral 1 denotes a stopper comprising a cork body 2 and a disk-shaped top or cap portion 3, of wood or other suitable material.

The periphery of the cap 3 is broached or serrated and is formed with a shallow peripheral groove 4 which is spaced slightly from the lower 30 peripheral edge 14 of the cap. Resiliently seated in the groove 4 is a split ring 5, of slightly resilient wire, bent intermediate its ends to form a loop portion 6. This loop portion is offset or bent downwardly, as at 7, and projects radially 35 from the groove for a purpose to be presently described. The ring, with the exception of the offset and protruding loop 6, is preferably flush with the periphery of the cap 3.

When the stopper is used on a whiskey bottle 40 or the like it is customary to place a sealing strip over the stopper, as well as the conventional revenue stamp, to prevent tampering with the contents of the bottle on which the stopper is used and to obviate danger of contamination 45 from extraneous matter. The stopper 1 is first inserted in the mouth of a bottle 8 and the conventional sealing strip or band 9 of "Cellulose" or similar material, is then applied to the bottle so as to cover and completely seal the split ring, 50 with the exception of the loop portion 6 which projects through a relatively small hole or opening 10 formed in the strip, during the application of the latter.

The legs or sides 11 of the loop 6 are bent inwardly, or pinched slightly together, approxi-

mately in the middle of the loop, to provide a purchase for the nails of the thumb and forefinger of the person opening the bottle. The inner ends of the legs 11 are also preferably flattened and sharpened to provide oppositely disposed cutting edges 12, at a point slightly below or offset from the juncture of the legs with the body portion of the ring, and in the same horizontal plane as that of the peripheral edge 14 of cap 3. Due to the fact that the loop protrudes 10 through the sealing strip, in order to open the bottle, it is merely necessary to hold the latter firmly in one hand, grasp the loop with the thumb and forefinger of the other hand and rotate the split ring in either direction, in an obvious 15 manner.

By virtue of the offset position of the cutting edges and looped portion with respect to the horizontal axis of the main body of the split ring, one of the cutting edges, depending upon 20 the direction of rotation, will form a circular cut through the sealing strip on a plane with the top marginal edge 15 of the bottle opening or mouth. In other words, the offset cutting edges of the loop compensate for the slight gap 25 between the peripheral groove 4 in the cap 3 and the lower edge 14 of the cap, occasioned by the necessary spacing of the groove from the lower edge of the cap. Thus, upon actuation 30 of the loop, as hereinbefore explained, the sealing strip is neatly severed and leaves no portion thereof extending above the annular rim 15 surrounding the filling and pouring opening 16, to form a lip or skirt which would impede the pouring of liquid, when the stopper is removed. The 35 presence of such a lip would result in the liquid spilling or slopping over the mouth of the bottle. The novel cutting arrangement, herein described, obviates the heretofore necessary expedient of removing this objectionable portion by 40 means of a knife or other sharp instrument with consequent danger of destroying the revenue stamp or stopper.

Having thus described my invention, what I claim is:

1. A combined bottle stopper and seal comprising a stopper having a cap portion, said cap portion having a peripheral groove formed therein, a split ring seated in said groove and having a loop portion thereon, a band of flexible sheet material on said stopper for sealing said cap portion and said ring to the neck of a bottle, said loop portion being offset from the horizontal axis of said ring and formed with cutting edges for cutting said band.

2. A combined bottle stopper and seal comprising a stopper having a cap portion, said cap portion having a peripheral groove formed therein, a split ring seated in said groove and having a loop portion intermediate its ends, said loop being formed with cutting edges and being offset with respect to the horizontal axis of the ring, and a band of flexible sheet material on said stopper for sealing said cap portion to the neck of a bottle, said loop extending through said band.
3. A bottle stopper adapted for use with flexible sealing strips comprising a peripheral cap
- 5
- 10

portion, a groove formed in said portion, and a split ring seated in said groove, said ring having a gripping and cutting portion formed thereon and offset from the horizontal axis of the ring.

4. A bottle stopper adapted for use with flexible sealing strips comprising a peripheral cap portion having a groove formed therein, a resilient split ring seated in said groove, said ring having a loop portion intermediate its ends formed with a cutting edge, said loop portion being positioned below the horizontal axis of the ring.
